UNITED STATES PATENT OFFICE.

WILLIAM LEWIS, OF UTICA, NEW YORK.

BED-SPRING.

1,111,075.

Specification of Letters Patent. Patented Sept. 22, 1914.

Application filed December 24, 1910. Serial No. 598,130.

To all whom it may concern:

Be it known that I, WILLIAM LEWIS, of Utica, in the county of Oneida and State of New York, have invented certain new and useful Improvements in Bed-Springs; and I do hereby declare that the following is a full, clear, and exact description thereof, which will enable others skilled in the art to which it appertains to make and use the same, reference being had to the accompanying drawings, and to the reference-numerals marked thereon, which form part of this specification.

My invention relates to coil springs adapted for use in bed springs, sofas and similar upholstered articles, reference being had to my pending application No. 834,316, filed April 25, 1914, and allowed May 11, 1914.

My construction is an improvement and modification of the class of such springs generally called two-cone springs.

The general object of my invention is to provide such a spring of improved form and construction which will combine the necessary resiliency for ease and strength to resist undue compression. With the construction I use to obtain these results, I also am able to make certain novel detail constructions which will more fully appear hereafter.

Figure 1 is a side elevation of a spring embodying my general construction. Fig. 2 is a perspective view of the same. Fig. 3 is a perpendicular sectional view, crosswise of a bed spring embodying one form of my invention. Fig. 4 is a perpendicular sectional view lengthwise of the head end of a bed showing one method of using my spring.

The coils A of my spring are preferably formed of a single piece of suitable spring wire bent to form a coiled spring of three sections. The two outer or end sections 5 and 6 and which for convenience I will call the top and bottom sections respectively, are in the form of the well known two-cone spring, that is having the larger convolutions at the top and bottom respectively and the smaller convolutions toward each other.

Between these two cone sections and connecting them, I form a central cylindrical section 7 in which the convolutions are of relatively small diameter, preferably of about the same diameter as the adjacent or inner convolution of the sections 5 and 6.

At the top and bottom ends of the cylind-

rical section 7 each coil is intersected by upper and lower braces 8 and 9, respectively, extending lengthwise of the bed and intersecting in the same way each coil spring in a given row. The braces are secured to the coils by any suitable means such as a raised offset 10 in the braces 8 and 9, which will fit within the convolutions 5^a and 7^a respectively of the coil above the braces and will be held thereby by the convolutions 7^b and 6^b respectively below, which are formed so close to the convolutions next above as to keep the braces in place after they have once been forced into position. The purpose of these braces is to keep the coils in a perpendicular position and to prevent them from turning sidewise or "buckling" when they are placed under pressure. The braces are of sufficient stiffness to keep each coil in line with the rest of the coils in its row and distribute to adjacent coils a part of the weight that may come on one coil.

At intervals through the length of the bed spring there are upper and lower cross braces 11 and 12 respectively which intersect the coils of that row at the same point as the braces 8 and 9, and are securely fastened thereto as by rivets 13. These cross braces serve to further secure the coils in perpendicular position. Fig. 2 represents a coil which is intersected by both lengthwise and crosswise braces while Fig. 1 represents a coil that has only the lengthwise braces.

As pressure is applied to a spring of this construction the larger convolutions will be compressed easily and therefore first. As further pressure is applied the convolutions midway of the cone sections 5 and 6 will contract and the smallest convolutions which are those in the middle or cylindrical section 7 will be brought into play last because they are the strongest. In this way the middle section 7 acts as a reserve strength in the spring which prevents the spring from being compressed its total available amount under ordinary strain and yet does not have the undesirable and uncomfortable hardness of an entirely unyielding stop or limit. By forming the spring in this triple-deck form with two layers of braces, I am able to use if desired a coil of greater total height than where only one brace is used. It is not necessary, however, to use a coil of greater height than usual, as the peculiar construction herein described provides a spring of

sufficient elasticity to make it comfortable while the reserve strength of the middle section allows for unusual strain.

Fig. 3 shows how my construction may be used to advantage on an iron bed, having the usual cross bars 14 of angle iron the ends of which are supported on the side rails 15. Just within the side rails, the cross bars are bent downwardly some distance and then extend across the bed horizontally. This depression allows a greater depth of spring to be used without raising the surface of the bed spring. The difficulty heretofore has been with the coil nearest the edge of the bed. The coil located on the edge, would have to be of considerable less height than the coils in the rest of the bed as of course the edge of the bed could not be higher than the rest of the springs. If an ordinary coil of this lessened height were used, it would be so much weaker proportionately than the rest of the coils that comparatively little weight would contract the coil its full amount.

It is well known that the edge of a bed has to receive the greatest strain and that this strain can not be distributed over as large a number of coils as strain at other parts of the bed. This great strain and excessive contraction makes the ordinary coils on the edge uncomfortable in use and soon renders them valueless. The same disadvantages arise whether the short coil be formed as a two-cone spring or as a one cone spring. I obviate these difficulties by placing at the edge a modification of my three-section spring A which modification is designated B in Fig. 3 and consists of an upper cone shaped section 16 and a lower section 17. The upper section 16 of this spring B is similar to the upper section 5 of the spring A and the lower section 17 of the spring B is similar to the middle section 7 of the spring A. The depression in the cross bar 14 will be of about the same extent as the height of the bottom section 6 of the springs A which will be used in the rest of the bed spring. The upper and lower cross braces 11 and 12 respectively will therefore be extended across on a line from coils A to coils B in the same way as coils A are connected thereby. Intersecting the coils B at the junction of the upper section 16 with the lower or cylindrical section 17 is a brace 18 extending lengthwise similar to brace 8 and connected to the coil B in a similar manner and for the same purpose. The bottom of sections 17 rest upon a strip 19 and are secured thereto by clips 20 rising from said strip and turned over the lower convolution of section 17 in the well known manner. This strip rests upon the ends of the cross bars 14 and is secured thereto by a rivet 21. In the rows having a cross brace

12, that cross brace may be inserted between the strip 19 and cross bar 14 and secured by the same rivet 21. The upper and lower convolutions of the coils will be flexibly connected to the similar convolution of adjacent coils as by links 22. A rod 23 extends along the outer edge of the bed spring, being threaded through the upper convolutions.

Fig. 4 illustrates another useful combination I make by means of my invention and which I call a raised head construction. I place two rows of my triple-deck coils A across the head of the bed and use ordinary two-cone coils C for the rest of the bed spring. The lower lengthwise brace 9 of my coils A will be extended through the bed to form the usual brace of the coils C. The upper lengthwise brace 8 of my coils A will not extend beyond the coils A. Both rows of these coils A will be connected with the upper cross brace 11 and the row of coils A at the head of the bed will have a lower cross brace 12. The head of the bed spring thus formed is higher than the rest of the bed by reason of my using three-section coils A of greater total height than the height of the coils C. This raised head construction raises the head of the person using the bed to a natural and easy position without the use of a pillow or with less pillow than would otherwise be needed. The advantages are that the head rest so secured, will not be displaced or so compressed as to be useless as is commonly the result with a pillow. It will be noted that the extra height for this head rest is secured by using higher coils at the head of the bed and that this extra height can only be secured where adequate means are provided for preventing these extra high coils from buckling. I provide these extra high coils and also means for maintaining such coils in perpendicular position. By inspection of Fig. 4 it will be seen that this combination of coils A and C can be made very easily and without any extra parts as the lengthwise brace 9 extends through coils A and C and the usual links 22 tie the top convolution of coil A to the top convolution of the adjacent coil C which does away with any too abrupt slope in the surface of the bed.

It is obvious that a similar combination of high strong coils with shorter ones can be made in other parts of the bed to strengthen if where needed or desired. For instance a row or two of coils A down through the center of the bed would so strengthen it as to overcome the usual tendency of a bed allowing two persons in a bed to roll or slide toward each other at the center of the bed. I have not illustrated this in the drawings as there would be no structural difference between this construction and that shown in Fig. 4 except that a series

of coils C would be placed at the left of the coils A as well as at the right as now shown.

What I claim as new and desire to secure by Letters Patent is—

- 5 1. The combination in a bed spring of a series of coils at the edge of the bed, having two sections, the upper of which is cone shaped and tapers toward the lower and the lower of which is formed of comparatively 10 small convolutions, coils in the balance of the bed of greater height and composed of three sections, the upper and lower of which are cone shaped and taper toward each other, the middle section of which is 15 of smaller convolutions, braces connecting the upper junction points of said three section coils and the junction points of the two section coils and braces connecting the junction points of adjacent two section coils, 20 and braces connecting the lower junction points of the three section coils, and cross bars depressed between their ends to support the higher coils and supporting the said two section coils at the raised ends.
- 25 2. The combination in a bed spring of a series of coils at the edge of the bed having two sections, the upper of which is cone shaped and tapers toward the lower and the lower of which is formed of comparatively 30 small convolutions, coils in the balance of the bed of greater height and composed of three sections, the upper and lower of which are cone shaped and taper toward each other and the middle section of which 35 is of smaller convolutions, braces connecting the upper junction points of said three-section coils and the junction points of the two-section coils and cross bars depressed between said ends to support the higher 40 coils and supporting the said two-section coils at the raised ends.
3. The combination in a bed spring of a series of coils at the edge of the bed having two sections, the upper of which is cone 45 shaped and tapers toward the lower and the lower of which is formed of comparatively small convolutions, coils in the bal-

ance of the bed of greater height, braces connecting the junction points of the two-section coils and intermediate points upon 50 said higher coils and cross bars depressed between their ends to support the higher coils and supporting the said two-section coils at the raised ends.

4. The combination in a bed spring of a 55 series of coils at the edge of the bed having two sections, the upper of which is cone shaped and tapers toward the lower and the lower of which is formed of comparatively small convolutions, coils in the balance 60 of the bed of greater height, braces connecting the junction points of the two section coils and intermediate points upon said higher coils, braces connecting adjacent intermediate points upon said higher 65 coils and cross bars depressed between their ends to support the higher coils and supporting the said two-section coils at the raised ends.

5. A triple deck spring for spring beds 70 comprising coaxial end and intermediate sections, the end sections being conical and tapered toward the intermediate section and the intermediate section of smaller diameter than the larger ends of the conical end sections, and separate floating brace bars interlocked with the junctions of the end sections with the intermediate section.

6. A triple deck spring for spring beds comprising conical end sections and a relatively 80 smaller intermediate section, convolutions at the junctions of said sections being closer together than the remaining convolutions and separate floating brace bars inserted between the juxtaposed convolutions 85 at the junction of said sections.

In witness whereof I have affixed my signature, in the presence of two witness, this 17th day of December 1910.

WILLIAM LEWIS.
